DESIGN FOR AN EMBROIDERED TRIMMING

Franz Hoenig, New York, N. Y.

Application May 14, 1940, Serial No. 92,358

Term of patent 3½ years

To all whom it may concern:

Be it known that I, Franz Hoenig, a citizen of the United States of America, residing in New York city, in the Borough of Manhattan, county and State of New York, have invented a new, original, and ornamental Design for an Embroidered Trimming, of which the following is a specification, reference being had to the accompanying drawing, forming part thereof, wherein the figure is a plan view of an embroidered trimming showing my new design.

I claim:

The ornamental design for an embroidered trimming, substantially as shown.

FRANZ HOENIG.
